(57) **CLAIM**

The ornamental design for a communication device, as shown and described.

DESCRIPTION

FIG. 1 is an isometric view of an ornamental design for a communication device showing our new design;

FIG. 2 is a front orthographic view thereof;

FIG. 3 is a rear orthographic view thereof;

FIG. 4 is a top orthographic view thereof;

FIG. 5 is a bottom orthographic view thereof;

FIG. 6 is a right side orthographic view thereof; and,

FIG. 7 is a left side orthographic view thereof.

The broken lines shown in FIGS. 1-7 that are immediately adjacent to the shaded areas, and encompass unshaded regions, represent the bounds of the claimed design, while all other broken lines are directed to environment and are for illustrative purposes only; the broken lines form no part of the claimed design.
